UNITED STATES PATENT OFFICE.

ELISHA L. RADER, OF SEATTLE, WASHINGTON, ASSIGNOR TO METROPOLITAN WINDOW SHADE COMPANY, OF SEATTLE, WASHINGTON, A CORPORATION OF WASHINGTON.

CLEANSING COMPOUND.

1,196,282.

Specification of Letters Patent. Patented Aug. 29, 1916.

No Drawing.

Application filed December 6, 1915. Serial No. 65,400.

To all whom it may concern:

Be it known that I, ELISHA L. RADER, a citizen of the United States, residing at Seattle, in the county of King and State of Washington, have invented a certain new and useful Improvement in Cleansing Compounds, of which the following is a specification.

This invention relates to cleansing compound and has special reference to a chemical compound made by mixing certain chemical ingredients together in definite proportions by means of which an improved cleansing fluid is produced.

The principal object of the invention is to provide a compound wherein certain chemicals will be combined to produce an improved cleansing compound which will be adapted for use on dyed fabrics without injuring the color.

My composition consists of the following ingredients combined in the proportions stated, viz: One third of a pound of sodium carbonate, one fifth of a pound of oxalic acid, one quarter of a pound of sodium sul-

fite, one gallon of water. These ingredients are mixed in the following manner: The sodium carbonate, oxalic acid and sodium sulfite are put into one gallon of water to dissolve therein and the mixture is then heated until it boils and thereupon the mixture is allowed to cool whereupon it may be bottled for distribution. 30

By the use of a sponge the above composition may be applied to window curtains and other fabrics thoroughly to clean such window curtains and fabrics and to restore their original colors. 35

What I claim is:

A cleansing compound consisting of a mixture of oxalic acid, sodium carbonate, and sodium sulfite in hot water in the proportions and manner as set forth. 40

In witness whereof, I, hereunto subscribe my name this 29th day of November A. D., 1915. 45

ELISHA L. RADER.
